UNITED STATES PATENT OFFICE.

JOHN FRANCIS MURPHY, OF ADRIAN, MICHIGAN, ASSIGNOR TO GEORGE B. M. SEAGER AND HERBERT R. CLARK, OF ADRIAN, MICHIGAN.

DRESS-SHIELD HOLDER.

SPECIFICATION forming part of Letters Patent No. 696,689, dated April 1, 1902.

Application filed February 14, 1901. Serial No. 47,303. (No model.)

To all whom it may concern:

Be it known that I, JOHN FRANCIS MURPHY, a citizen of the United States, residing at Adrian, in the county of Lenawee and State 5 of Michigan, have invented a new and useful Dress-Shield Holder, of which the following is a specification.

This invention relates to dress-shield holders, the object in view being to provide a simple holding device for securely fastening a dress-shield within the arm-scye of a garment, so that there is no liability of the dress-shield to become disengaged while the garment is worn. After removing the garment from the 15 person the holder may be readily disconnected from the garment, and is thus capable of being easily disconnected from one garment and applied to another.

Another object of the invention is to provide a dress-shield holder which is entirely covered and concealed and protected by the shield, thereby preventing any part of the holder from coming in contact with the skin or undergarment. The holder is made of thin 25 flexible material, such as light sheet metal, which will readily give to the movements of the arm and body, thus preventing any inconvenience to the wearer.

Another object of the invention is to provide a dress-shield holder composed of flexibly-connected members provided adjacent to their joints with complementary portions of dress-engaging clasps, the members of each 30 clasp being so arranged that by folding the dress-shield holder simultaneously with the dress-shield to which the members are attached the said clasp members will be opened to receive the seam or material of the dress adjacent to the arm-scye and when the shield 35 and holder are straightened out the said clasp members will automatically engage and obtain a firm hold on the material of the dress contiguous to the arm-scye.

With the above and other objects in view 40 the invention consists in a dress-shield holder embodying certain novel features and details of construction and arrangement of parts, as hereinafter fully described, illustrated in the drawings, and incorporated in the claims.

50 In the accompanying drawings, Figure 1 is a perspective view of a dress-shield, showing

the holder therefor in dotted lines. Fig. 2 is a perspective view of the holder, with the dress-shield indicated by dotted lines. Fig. 3 is a detail perspective view of one of the 55 joints of the holder, showing the clasp members. Fig. 4 is a detail section through the shield and holder adjacent to one of the clasps, showing the latter in engagement with the arm-scye of a dress.

Similar numerals of reference designate corresponding parts in all the figures of the drawings.

Referring to the drawings, 1 designates a dress-shield of any ordinary or preferred construction, which is folded in the usual manner to form the bight 2. The holder contemplated in this invention is arranged between the side portions of the shield and directly within the bight or fold 2, as clearly illustrated in the drawings. The holder is also coextensive in length with the width of the dress-shield, so as to extend throughout the length of the bight or fold and form a continuous support and spreader for the shield.

The holder is composed of several sections or members, and for convenience I have illustrated the holder as comprising three members, 3 designating the central or intermediate member, and 4 the outer or terminal members, which are connected flexibly by means of pivots 5 to the opposite ends of the intermediate member 3. The contiguous ends of the members are enlarged for the purpose of receiving the pivots by which they are connected, and adjacent to their points of pivotal connection the members are each provided with a terminal clasp member 6. By reference to Fig. 3 it will be seen that the clasp member on one of the holder-sections is of 85 less length than the other clasp member co-operating therewith and connected with the joining member, and the extremities of the clasp members are bent inward toward each other, so as to lie one slightly above and over the other, the object of which is to enable the in-bent extremities of the members of the clasp to engage over and embrace the seam of a garment within the arm-scye thereof, thereby effectually preventing the dress-shield holder from becoming detached as long as the arm is contained within the sleeve. It

is only when the dress-shield is folded or doubled and the holder-sections folded relatively to each other that the in-bent extremities of the clasp members are moved laterally out of engagement with each other and with the seam in the arm-scye, and during such folding movement of the dress-shield and holder the clasp members move in parallel planes. The intermediate member 3 is provided at both extremities with clasp members, while the outer or terminal sections of the holder are provided at their inner ends only with the clasp members, and the members of the clasp are so arranged relatively to each other and to the sections of the holder that they will be in their best operative positions for gripping the garment when the sections line up with the fold or bight of the dress-shield. Therefore when the dress-shield is in its normal position within the arm-scye the clasp members are firmly engaged with the garment, and it is only by removing the arm from the sleeve that the holder and shield may be folded or doubled sufficiently to disengage the clasp members from the garment and permit the shield to be removed for application to another garment. In order to securely attach the holder to the inside of the dress-shield, the holder-sections are provided at suitable points with perforations 7 for the purpose of receiving stitches, wherewith each of the sections of the holder is individually secured to the dress-shield.

From the foregoing description it will be seen that the holder is entirely protected and concealed within the bight of the shield and that it is therefore impossible for any portion of the holder to come in contact with the body of the wearer or in contact with the undergarments. It will also be understood that there is no danger of the holder and shield becoming detached from the garment as long as the garment is worn, for the reason that the holder cannot flex or fold sufficiently to move the clasps out of engagement with the material of the garment. In view of the fact that the device is fitted within the bight of the shield and snugly against the arm-scye portion thereof it forms a spreader for maintaining this part of the shield in a spread condition, so as to prevent rucking up thereof when in use, and thereby obviating a very disagreeable feature which is present in the common form of dress-shield when not provided with a spreader of the present type. However, when the arm is withdrawn from the sleeve the shield, together with the flexibly-connected sections of the holder, may be folded in such manner as to move the complementary portions of the clasp away from each other, allowing the same to release their hold upon the material of the garment, and thereupon the shield and holder connected thereto may be easily removed and with equal facility attached to any other garment desired. By means of the device hereinabove

described the necessity of stitching the dress-shields in place is obviated and the shields may be quickly interchanged and removed from one garment to another. At the same time the holders, by reason of the fact that they are constructed of light thin flexible material, will occasion no inconvenience to the wearer.

It will here be noted that the shape of the spreader is arcuate. It terminates at or short of the opposite edges of the shield and is terminally connected thereto, the remaining portions of the shield being entirely free therefrom and the arm-scye-engaging fastenings are carried intermediately of and by the spreader and projected at the convex side thereof. This combination and arrangement of parts is important and advantageous, as it anchors or fastens the intermediate portion of the spreader to the garment, and thereby prevents looseness and bulging up of the intermediate portion of the spreader to the annoyance of the wearer, as would be the case if it were terminally connected to the garment.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

What I claim is—

1. A dress-shield spreader and holder, comprising a flexible arcuate spreader-body corresponding in curvature to the concaved edge of a dress-shield and adapted to be arranged wholly within the bight or fold thereof, an intermediate portion of the spreader-body being provided with means projected at its concaved side for engagement with the arm-scye of a dress-waist to anchor the intermediate portion of the spreader-body and prevent upward bulging thereof, and means for fastening the spreader-body to a shield.

2. A dress-shield having an arcuate spreader fitted snugly within and against the back portion of the bight thereof and connected to said back portion only, the remaining portion of the shield being entirely free from the spreader, the latter comprising a plurality of members disposed in longitudinal succession with their adjacent ends overlapped and pivotally connected, and mutually-coöperating garment-engaging clamp members carried by the adjacent members of the spreader.

3. A dress-shield having an arcuate spreader fitted snugly within and against the back portion of the bight thereof and connected to said back portion only, the remaining portions of the shield being entirely free from the spreader, and the latter comprising flexibly-jointed members disposed in longitudinal succession, and mutually-coöperating garment-

engaging clamp members carried by the adjacent spreader members.

4. A dress-shield, having a spreader fitted snugly within and against the back portion of the bight thereof and connected to said back portion only, the remaining portions of the shield being free from the spreader, the latter comprising a series of members made of flat material pivotally connected at their meeting ends, and provided at their terminals with co-operating arm-scye-engaging clamp members.

5. A dress-shield having a spreader fitted snugly within and against the back portion of the bight thereof, and connected to said back portion only, the remaining portions of the shield being free from the spreader, the latter comprising a series of flexible pivotally-connected members disposed in a curved series, and an arm-scye-engaging clamp member carried by each member of the spreader.

6. A dress-shield, having a spreader carried snugly within and against the back portion of the bight thereof, and connected to said back portion only, the remaining portions of the shield being entirely free from the spreader, the latter being formed by three arcuate members disposed in longitudinal succession, the opposite ends of the intermediate member being overlapped by and pivotally connected to the inner ends of the respective terminal members, and mutually-co-operating garment-engaging clamping members carried by the ends of the intermediate

spreader member and the inner ends of the respective terminal members. 35

7. A spreader and holder for dress-shields, consisting of an arcuate body formed by a plurality of arcuate members disposed in longitudinal succession, the adjacent ends of opposite members being pivotally connected, each member having means for connection with the bight of a dress-shield, and mutually-co-operating arm-scye-engaging members carried by adjacent members of the arcuate spreader. 40

8. A spreader and holder for dress-shields, having pivotally-connected arcuate members disposed in longitudinal succession, one of which is provided with a laterally-offset clamp member which is extended from the concaved side of the spreader member and projected beyond the convexed side thereof, and the other spreader member having a clamp member which is projected transversely from the convexed edge of the spreader 45 and constructed to lie across and coöperate with the other clamp member for engagement with an arm-scye when the spreader members are brought into longitudinal alinement.

In testimony that I claim the foregoing as my own I have hereto affixed my signature in the presence of two witnesses.

JOHN FRANCIS MURPHY.
